TROLLEY SHOE

Ambrose Mazzola, Temple City, Calif.

Application December 30, 1953, Serial No. 28,289

Term of patent 14 years

(Cl. D26—1)

To all whom it may concern:

Be it known that I, Ambrose Mazzola, a citizen of the United States, residing at Temple City, in the county of Los Angeles, State of California, have invented a new, original, and ornamental Design for a Trolley Shoe, of which the following is a specification, reference being had to the accompanying drawing, forming a part thereof, in which:

Fig. 1 is a side elevational view of a trolley shoe showing my new design; and

Fig. 2 is a top plan view thereof.

I claim:

The ornamental design for a trolley shoe, as shown.
